WIND DEFLECTOR

Hugh W. Shumaker, 517 S. Jackson St., Moscow, Idaho

Filed Apr. 29, 1960, Ser. No. 60,374

Term of patent 14 years

(Cl. D14—6)

Fig. 1 is a perspective view of a wind deflector embodying my new design;

Fig. 2 is a side elevational view thereof on a reduced scale with a portion of the deflector broken away for convenience of illustration; and

Fig. 3 is a top plan view thereof.

The corner post shown in broken lines is included for illustrative purposes only.

I claim:

The ornamental design for a wind deflector, substantially as shown and described.
